UNITED STATES PATENT OFFICE.

WILLIAM H. ANDREWS, OF NEW HAVEN, CONNECTICUT, ASSIGNOR TO
MALLORY, WHEELER & CO., OF SAME PLACE.

DESIGN FOR A LOCK-CASE.

Specification forming part of Design No. 6,996, dated November 18, 1873; application filed November 11, 1873.
[Term of Patent 7 years]

To all whom it may concern:

Be it known that I, WILLIAM H. ANDREWS, of New Haven, in the county of New Haven and State of Connecticut, have invented a new Design for Lock-Case; and I do hereby declare the following, when taken in connection with the accompanying drawing and the letters of reference marked thereon, to be a full, clear, and exact description of the same, and which said drawing constitutes part of this specification, and represents a side view of a lock.

This invention relates to a design for the ornamentation of that class of locks known to the trade as rim-locks; and it consists in the ornamentation of the case, as shown in the accompanying illustration, and as hereinafter described.

The figures or ornamentation denoted in solid black are raised or in relief upon the surface of the lock. The ground or surface may

be smooth or matted. The peculiar features of the ornamentation are clearly shown in the drawing. The keeper, in cases where one is required, is made to conform to the latch-ease.

The relative arrangement of the screw-holes constitute no part of this design, as they may be more or less in number, and differently arranged; neither is the key-hole or spindle-hole to be considered as any part of the design, as the ornamentation may be used on either a latch-ease or a lock-case independent of each other, or combined, as shown in the accompanying illustration.

I claim as my invention—

The design for lock-case, as herein described, and shown in the accompanying illustration.

WM. H. ANDREWS.
